UNITED STATES PATENT OFFICE.

WALTER EVERETT MOLINS, OF DEPTFORD, LONDON, ENGLAND.

APPARATUS FOR USE IN FITTING TOGETHER BOXES OF THE SLIDE AND SHELL TYPE.

Application filed December 2, 1926, Serial No. 152,298, and in Great Britain December 8, 1925.

This invention is for improvements in or relating to an apparatus for fitting together boxes of the slide and shell type and has for its object the provision of means whereby a shell may be opened from its collapsed state so as to receive a loaded slide without the possibility of the same fouling the shell.

The present invention consists of a device for use on a machine for assembling the slide and shell of a slide and shell packed, which comprises means for feeding collapsed shells one at a time from a pile, a suction element adapted to draw upon the broad under side of the shell so as to retain the same in the desired position upon the bed of the machine, and an element adapted to engage with one of the remaining sides of shell and operable, independently of any lateral abutment located on or adjacent to the bed of the machine, to open the shell for the reception of a slide.

The invention is more particularly described with reference to the accompanying drawings, in which:—

Fig. 1 illustrates in plan the layout of a machine constructed to assemble the packets of the slide and shell type.

Fig. 2 is an enlarged plan view of one method of opening the collapsed shells.

Fig. 3 is a side elevation on the line A—A of Fig. 2.

Figs. 4 and 5 illustrate details of the valve mechanism used in conjunction with the suction device illustrated in Figs. 2 and 3.

Fig. 6 illustrates mechanism adapted to feed the collapsed shells towards the suction mechanism, and

Figs. 7 and 8 illustrate in plan and elevation a modification of the apparatus illustrated in Figs. 2 and 3.

Referring to Fig. 1, the slides 2 are placed in a stack in a magazine 4 which is arranged on one side of a conveyor 1 and comprises side members 4*, front members 5 and 6 and a bottom in the form of a reciprocating table 7. The table is reciprocated by means of an eccentric, driven from the main drive of the machine in the manner described in U. S. Patent No. 1,473,496. At the rear edge of the table is a pusher tooth 12 which passes through an opening to the back member 6 and upon the movement of the table moves one slide at a time from the bottom of the stack to a pair of continuously rotating rollers 13 which feed the slide between suitably curved plates 14 which bend up the longitudinal edges of the slide, after which the slide

passes to a further pair of rotating rollers 15 which deliver it on to the conveyor. In this position the slide may be filled with cigarettes in the manner described in U. S. Patent No. 1,188,368. In Fig. 1 a machine is illustrated with a batch of cigarettes delivered on to the slide 20, with a succeeding batch 21 located on a conveyor 16 which moves the cigarettes towards the conveyor 1.

When the loaded slide 20 is in the position illustrated in Fig. 1 the cross piece 1* mounted on the conveyor 1, makes contact with the rearwardly directed upward edge of the slide and carries the same through an L shaped channel 22 and suitably curved plates 24 which fold up the two end pieces 25 of the slide approximately into a vertical position and thereafter bends the said ends into approximately a horizontal position ready for the slide to be inserted in an open shell. The slide so folded is then carried by the conveyor into the position for insertion into a shell.

The collapsed shells B are stacked in a magazine 27 on the same side of the machine as the slide magazine. The magazine 27 is of a similar construction to the slide magazine and is provided with a small reciprocating bottom and pusher tooth for feeding the lowermost collapsed shell between continuously rotating rollers 28. The rollers 28 pass the shell between a continuously rotating sector 29 (Fig. 6) and one edge of the shell engages with an arm 30 pivoted at 31 and pressed into engagement with the shell by a cam 32 engaging with a finger 33 on the arm 30. The action of the sector 29 and the arm 30 causes the shell to be moved into a position inclined to the direction of the conveyor 1. The shell is moved into the inclined position against a guide stop 33' above a suction element 34 which is connected to a suction pump (not shown) through the valve mechanism illustrated in Figs. 4 and 5. The valve mechanism illustrated in Figs. 4 and 5 is controlled by a cam 35 operable from the main drive of the machine and timed so as to bring the suction element 34 into operation when the shell is correctly disposed above the same.

Referring to Figure 1, it will be seen that the shell is moved into an oblique position so that when it is opened the mouth of the same will lie transverse to the path of the on-coming loaded slide, whereupon part of the slide enters the mouth of the shell in the manner illustrated in Figure 2 without necessitating a transverse movement of either the shell or

the slide, and without requiring that the slide cease its steady forward movement. After the parts are positioned as shown in Figure 2, the slide carries the shell forwardly and the same is automatically inserted over the slide by mechanism which forms no part of the present invention. It is an important feature of this invention that there is imparted to the loaded slide a steady forward movement in contradistinction to the usual step by step movement in devices heretofore known.

When the suction element 34 comes into operation an upper movable suction element 36 is also brought into operation and engages with the upper broad side of the shell and adheres to the same due to the action of the valve mechanism hereinbefore described. After the upper suction element 20 has been brought into operation a bell-crank lever 37 operable by cam 38 driven from the main drive of the machine rocks the lever 39 to cause the spindle 41 to rotate about its axis. Secured fast to the spindle 41 is a link 42 which is connected to the arm 43 which carries the suction element 36. On the upward movement of the link 42, the arm 43 is moved upwardly and carries with it the upper broad side of the collapsed shell. The arm 43 is preferably connected to link 44 which is similar to the link 42 and ensures that the arm 43 is given a parallel motion. The free end of the lever 39 is connected to a spring which, when the cam 38 has raised 35 the arm 43 into its highest position, tends to draw the said arm downwardly.

When the cam has caused the shell to be opened out into its maximum position the valve controlling the suction members is 40 opened and the suction members become inoperative. After the suction members are released the cam 38 tends to raise the arm 43 still further, but due to the fact that the end of the arm 43 which is connected to the link 45 44 is fixed and the intermediate point which is connected to the link 42 is secured thereto through a spring connection 45, the arm 43 is rocked about the pivotal connection between it and the link 44 and the suction element 36 is raised above the upper surface of the shell so as not to interfere therewith as the slide and shell are removed by the conveyor 1.

The suction element 36 is preferably provided with an adjustable stop 46 which is adjusted to engage with one of the corners of the shell which are located adjacent to the conveyor 1 and operate through the narrow side wall 47 of the shell to hold the lower broad face of the shell flush with the bed of the machine so as to ensure that the oncoming slide will be easily inserted into the shell. The shell and the slide are thereafter assembled in the manner described in U. S. Patent No. 1,473,496 and the assembled pack-

ets move on to a platform from which they are removed by the operator.

Instead of the upper suction element 36 hereinbefore described the upper element may comprise the device illustrated in Figs. 7 and 8. The lower suction element is constructed in such a manner that when the shell is moved directly above the same, the lower suction element conforms to the junction line between the lower broad side of the shell and that narrow side wall of the same which lies flush with and forms a continuation of the lower broad side when the shell is in the collapsed state.

The suction element 34 is adapted to draw the shell upon the bed of the machine along the entire line which constitutes the junction between it and the adjacent wall and thereby removes any bow that may exist upon the underside of the shell.

Mounted above the lower suction element 34 is a plunger 50 connected to links similar to those described with reference to Figs. 2 and 3, so that when the plunger is depressed it presses upon the upper surface of the collapsed shell and also permits a hook shaped projection 51 to engage with that narrow side wall of the shell which lies flush with the lower broad side of the shell.

The projection 51 on the end of the plunger 50 engages with the narrow side wall of the shell and swings the same upwardly about the junction line until the two narrow side walls of the shell are located at right angles to the lower broad side of the shell.

When the shell is in this position, the foremost corner of the advancing slide enters the inside edge of the shell and together with the conveyor 1, the slide and shell are moved forwardly and the slide and shell assembled 105 in the manner described in U. S. Patent No. 1,473,496.

What I claim as my invention and desire to secure by Letters Patent is:—

1. A device for use on a machine for assembling the slide and shell of a slide and shell packet which comprises in combination means for feeding collapsed shells one at a time from a pile, means adapted to impede the movement of one side of the shell relatively to the other, a suction element adapted to draw upon the broad under-side of the shell so as to retain the same upon the bed of the machine in the desired position for the insertion of a slide and a second suction element adapted to engage with the other broad side of the shell and operable in conjunction with said first suction element and independent of any lateral abutment located on or adjacent to the bed of the machine to open completely the shell for the reception of a slide.

2. A device for use on a machine for assembling the slide and shell of a slide and shell packet which comprises means for feed-

ing collapsed shells one at a time from a pile, means adapted to feed one side of the shell forwardly while the other is impeded, a suction element adapted to apply pressure to the 5 broad underside and along a line adjacent the junction line between the said broad under-side of the shell and one narrow side thereof, and an element adapted to engage with one other side of the shell so as to swing 10 the same about the junction line between the broad end panel and the next adjacent narrow panel of the shell.

3. A device for use on a machine for assembling the slide and shell of a slide and 15 shell packet which comprises means for feeding collapsed shells one at a time from a pile, means adapted to feed one side of the shell forwardly while the other is impeded, a suction element adapted to apply pressure to the 20 broad underside and along a line adjacent the junction line between the said broad under-side of the shell and one narrow side thereof, and a second suction element movable 25 into engagement with the upper broad side of the shell and movable away from the lower element to open the shell and bow the upper face thereof, and a stop adapted to depress at least one corner of that end of the open shell which is located adjacent to the advancing slide so as to ensure that the lower broad face 40 or a portion thereof lies flush with the advancing slide.

4. A device for use on a machine for assembling the slide and shell of a slide and 30 shell packet which comprises means for feed-

ing collapsed shells one at a time from a pile, means adapted to feed one side of the shell forwardly while the other is impeded, a suction element adapted to apply pressure to the broad underside and along a line adjacent the junction line between the said broad under-side of the shell and one narrow side thereof, a second suction element movable 35 into engagement with the upper broad side of the shell and movable away from the lower element to open the shell and bow the upper face thereof, and a stop adapted to depress at least one corner of that end of the open shell which is located adjacent to the advancing slide so as to ensure that the lower broad face 40 or a portion thereof lies flush with the advancing slide.

5. In apparatus for feeding articles, the combination with a rotatable sector for engaging and feeding articles forwardly, of a pivoted element, and means for periodically moving said element into engagement with a moving article adjacent one side thereof, whereby the forward movement of the engaged side is retarded for rotating the article into an inclined position.

In testimony whereof I hereunto affix my signature.

WALTER EVERETT MOLINS.
